UNITED STATES PATENT OFFICE.

ROBERT E. FRIEDEIN, OF NEW YORK, N. Y., ASSIGNOR TO JACOB WHEATFIELD, OF NEW YORK, N. Y.

LABELING-MACHINE.

1,007,550.

Specification of Letters Patent. Patented Oct. 31, 1911.

Application filed June 29, 1911. Serial No. 636,074.

To all whom it may concern:

Be it known that I, ROBERT E. FRIEDEIN, a citizen of the United States, residing at New York, in the county of New York and State of New York, have invented certain new and useful Improvements in Labeling-Machines, of which the following is a specification.

My invention relates to improvements in labeling machines, and it consists in the constructions, combinations and arrangements herein described and claimed.

An object of my invention is to provide an improved labeling machine having a capacity greater than that of previous constructions.

A further object of my invention is to provide an improved labeling machine, in which the several operating parts are yieldingly actuated throughout their working strokes; thereby eliminating all danger of injurious contact or interference between the moving parts upon breakage or accidental displacement of the actuating means.

A further object of my invention is to provide an improved labeling machine, in which the boxes, or other articles operated upon, are fed from a plurality of independent supplies to a common labeling and delivery compartment; thereby providing a compact and durable construction capable of furnishing a large output with a relatively slow operation of its working parts.

In the accompanying drawings, forming a part of this application and in which similar reference characters indicate corresponding parts in the several views: Figure 1 is a front elevation, partly broken away at the base and top, illustrating one embodiment of my invention; Fig. 2 is a side elevation of the construction shown in Fig. 1, with the left-hand frame bracket broken away; Fig. 3 is an enlarged front view of one of the label holders and its actuating means; Fig. 4 is an enlarged section of the labeling compartment and plunger, taken on the line 4—4 of Fig. 1; Fig. 5 is a detail view of the upper part of Fig. 4, showing the plunger in its depressed position; Fig. 6 is an enlarged front view of the grippers and the stops coöperating therewith, and Fig. 7 is a reduced plan view of the reciprocating feed slide.

Referring to the drawings, 1 indicates a

pair of independent supply chutes secured to a frame 2 and provided with open upper ends for receiving boxes, or other articles; the boxes being fed by gravity to base plates 3 of said chutes in the path of a reciprocating feed slide 4. The feed slide 4 is reciprocated by an oscillating crank 5, having a slotted engagement with a pin 6 on said slide and journaled at 7 in the frame 2; a swing arm 8 being rigidly secured to the crank journal 7 and provided with a slotted end 9 for engaging a pin 10 on a lever 11. The lever 11 is pivoted on the lower portion of the machine frame, and carries a roller 12 in engagement with the slot 13 of a rotating cam 14; whereby said lever will be given a double oscillation upon each revolution of the cam 14. A pair of paste pots 15 are supported on the machine frame and provided with rollers 16 for feeding paste, or other adhesive material, to paste platens 17, which latter reciprocate in guides on said pots to bring their paste-supplying surfaces 18 alternately over the feed rollers 16 and label holders 19; said platens being reciprocated by links 20 connecting them to levers 21, which are pivoted at 22 to the frame and maintained by springs 23 in yielding engagement with cams 24. By this construction, the springs 23 tend to retract the platens for receiving a supply of paste from the rollers 16, and the cams 24 project the platens to bring their surfaces 18 over the label holders, as shown in Fig. 2.

Each holder 19 carries a stock of labels 25 and is recessed to snugly receive a traveling head 26; said holders being provided with slots 27 for receiving pins 28 on said heads and with spring-pressed latches 29, which engage said heads and coöperate with said slots and pins to detachably lock the holders firmly in position. By this improved construction, an empty holder can be instantly removed and replaced by a filled holder, thereby permitting the supply of labels to be replenished without loss of time in the operation of the machine. Brackets 30 are provided with guides 31 slidably receiving rods 32 on the traveling heads 26, and with guides 33 for rods 34 which actuatingly engage said heads 26. A sleeve 35 is slidably mounted on each rod 34 and carries a pawl 36, constructed to ride upwardly over a rack 37 on said rod but to

depress said rod when engaging the rack during the downward movement of said sleeve 35. The sleeve 35 is depressed by a lever 38 pivoted at 39 to the machine frame, and held in yielding contact with the cam 24 by springs 40 connected to the rod 34 and bracket 30. When the recessed portion 41 of the cam 24 is presented to the lever 38, the springs 40 raise the rod 34 and carry up the sleeve 35 and forward end of the lever 38 by engagement of the rack 37 on said rod with the pawl 36; a stop 42 being suitably positioned on the bracket 30 to engage said pawl and release the latter from the rack 37 upon the lever 38 reaching its uppermost position. Upon such release of the pawl, the springs 40 tend to further elevate the rod 34 through the slidable sleeve 35 and raise the label holder 19 until such movement is stopped by engagement of the top label in said holder with the surfaces 18 of the paste platen 17. The continued rotation of the cam 24 then depresses the forward end of the lever 38 and the sleeve 35 carried thereby, and depresses the rod 34 by engagement of the pawl 36 with whichever tooth of the rack 37 is in position to receive said pawl upon the latter's travel from contact with the stop 42.

From the above description, it will be clear that all down strokes of the rod 34 under the action of the pawl 36 are of equal length, and that said rod is gradually fed farther upward through the slidable sleeve 35 by the springs 40 as the labels 25 are successively fed to the paste platen. The rod 34, thus, automatically adjusts the label holder relatively to the paste platen, in order to maintain a uniform stroke of said holder throughout the successive feeding of the entire stock of labels 25 to the paste platen. This constitutes a novel and valuable construction, which enables the holders 19 to be stocked with an advantageously large number of labels, without necessitating a corresponding increase in the stroke or travel of said holders. For example, in my improved construction, holders having a stroke of less than an inch can accommodate a stock of a thousand or more labels.

A stripper 43 is slidably mounted on the rods 32, and supported in position by a lip 44 which projects to rest upon the top of the stock of labels 25 in the holder 19; said stripper being advantageously formed of a plate of resilient metal. By this construction, the stripper is raised by its lip 44 each time the stock of labels 25 is elevated to present the top label thereof to the paste-platen surfaces 18; and, upon depression of the label holder 19 by the cam 24, the stripper falls by gravity and its lip 44 in passing below the top label, which is adhering to

the paste-platen surfaces 18, slightly deflects the edge of said label and detaches any additional labels which may adhere to said top label. This provides a novel and efficient construction, in which the stripper will 70 act uniformly throughout the successive feed of the entire stock of labels.

A gripper plate 45 is slidably mounted in the supporting bases 46 of the paste pots 15, and carries duplicate sets of grips for 75 conveying labels alternately from each paste platen 17 to a common labeling compartment; said slide being reciprocated by a roller 48 on the front end of the pin 10 carried by the lever 11. Each set of grips 80 comprises a lower jaw 49 rigidly carried by the gripper plate 45 and a pivoted upper jaw 50; actuating arms 51 being rigidly secured to the pivots of said upper jaws and connected by springs 52 to the plate 45 for 85 normally maintaining said jaws in closed position. The arms 51 are positioned at different distances from the front of the machine, in order to selectively engage similarly positioned stops 53 and pivoted 90 latches 54 upon reciprocation of the gripper plate 45.

Referring to Figs. 1 and 6 of the drawings, it will be understood that, upon approach of the gripper plate 45 to its extreme right-hand position, the actuating arm 51 of the right-hand grip will engage the latch 54 and open said grip to receive a label adhering to the adjacent paste platen; the final, slight, further movement to the right causing said 100 arm 51 to ride beneath the latch 54 which then yields upwardly, whereupon the spring 52 will swing said arm and its attached jaw 50 to close the grip on the label previously received between its open jaws. During such movement to the right, the arm 51 of the left-hand grip will engage the adjustable stop 53, and swing said arm and its attached jaw 50 to open the grip for releasing a label which has been carried thereby 110 from the left-hand paste platen to the labeling compartment. Upon reciprocation of the gripper plate 45 to the left, the right-hand grip will carry the label thus held thereby to the labeling compartment, and release such label upon engagement of the actuating arm 51 with the adjustable stop at 115 the left of the machine. During completion of such movement to the left, the actuating arm 51 of the left-hand grip will engage the adjacent latch 54 for opening and closing said grip to receive and grip a label adhering to the left-hand paste platen, in the previously described manner. This improved 120 construction provides a simple and accurate means for supplying labels alternately from opposite sides to the common labeling compartment, thereby permitting a rapid 125 supply of labels with a relatively slow movement of the gripper device.

The labeling compartment comprises an open-ended chute having a rear wall 55 and side walls 56 and 57 supported from the machine frame. A plate or liner 58 is resiliently supported, as by a spring 58^a, on the wall 57 to yieldingly engage the boxes or packages for frictionally supporting the latter during their passage through the compartment; said plate having sufficient movement to accommodate slight irregularities and differences in the sizes of such boxes.

The boxes are fed through the labeling compartment by a plunger 59 carried by rods 60 extending from a cross head 61 through guides 62 on said compartment; said head and plunger being normally maintained in depressed position by a weight 63, shown attached to said head. A lever 64, fulcrumed on the frame at 65, carries a roller 66 engaging the head 61; said lever being actuated by a rotating cam having a pair of diametrically opposed depressed surfaces 67 for elevating the head 61 and plunger 59. This provides a very efficient construction, in which the boxes are forced through the labeling compartment under the constant and yielding force of the weight 63; thereby avoiding all danger of an augmented or excessive pressure being exerted on the boxes through accidental displacement or jamming of the latter, and preventing crushing or injury of said boxes.

A shutter 68 is pivoted at 69 to the lower portion of the labeling chute in position to swing upwardly into sliding engagement with the front face of the plunger 59; whereby said shutter constitutes a front wall for the labeling compartment and a retaining guide for the boxes while the latter are being fed by the plunger to said compartment. The shutter 68 is detachably supported in operative position, as by a yoke 70 detachably secured by bolts 71 to the guides 62 and carrying an adjustable screw 72 for engaging said shutter. This provides an advantageous construction, by which the shutter can be conveniently swung downward to permit ready inspection or removal of the boxes within the labeling compartment. A spring clip 73 depends from the rear face of the plunger 59 for coöperation with the shutter 68 to resiliently clamp and support the boxes fed therebetween from the supply chutes 1 by the reciprocating feed slide 4; said clip being provided with a curved extension 74 for engaging the rear wall 55 of the labeling compartment to release the box when the plunger 59 has been depressed to direct said box into the compartment. During such depression of the plunger 59, the box carried thereby is directed onto a label which has been previously supplied with paste and deposited across the top of the labeling compartment by the grips, as above described; the movement of the box into said

compartment carrying the label with it, and leaving the paste-carrying ends of the label upstanding at the opposite sides of said box. Links 75 are pivoted at 76 to bell-crank levers 77, which are fulcrumed at 78 on opposite sides of the labeling compartment; the free ends of said links being provided with suitable means, such as rollers 79, for folding over the paste-carrying ends of the label and pressing them over the box to cause their certain adhesion to the latter. The rollers 79 are actuated on their folding stroke by rods 80 slidably mounted in guides 81 and engaging the levers 77 and intermediate bell-crank levers 82 fulcrumed at 83; said levers 82 being actuated by cams 84, which are set on a common shaft 85 to actuate one of said links 75 slightly in advance of the other, for preventing interference between the rollers 79 on said links. Tension springs 86 are connected to the pivoted links 75 and to the guides 81, or other stationary part of the machine, for maintaining an efficient yielding pressure of the rollers 79 in pasting the label to a box; said springs 86 acting to retract the links 75 and levers 77 upon release of the levers 82 from the cams 84.

It will be noted that the grips, feed slide, paste platens, label holders, and plunger 95 are actuated by cams 14, 24, and 67 secured to a common shaft 86; whereby said several cams constitute, in effect, a single rigid cam device, and thus insure accurate timing, or relative operation, between the several operating parts.

I have illustrated preferred and satisfactory constructions, but changes could be made within the spirit and scope of my invention.

I claim:

1. In a labeling machine, the combination of a series of supply chutes, a common labeling compartment, a plunger for directing articles through said compartment, and a feed device for delivering articles successively from said several chutes to said plunger.

2. In a labeling machine, the combination of a pair of supply chutes, a common labeling compartment, a plunger for directing articles through said compartment, and a reciprocating feed device for delivering articles alternately from said pair of chutes to said plunger.

3. In a labeling machine, the combination of a common labeling compartment, a series of supply chutes and paste platens, means for delivering articles from said chutes to said compartment, and means for delivering labels from said platens to said compartment.

4. In a labeling machine, the combination of a common labeling compartment, a series of supply chutes and paste platens, means

for delivering articles from said chutes to said compartment, means for delivering labels from said platens to said compartment, and a single cam for actuating said means for delivering the articles and labels.

5. In a labeling machine, the combination of a series of supply chutes, a corresponding series of paste platens, a common labeling compartment, a plunger for directing articles through said compartment, a feed device for delivering articles successively from said several chutes to said plunger, and means for delivering labels successively from said several platens to said common labeling chamber.

10. 6. In a labeling machine, the combination of an open-front labeling compartment, a plunger for directing articles through said compartment, a front closure for said compartment, and adjustable means for detachably maintaining said closure in sliding engagement with said plunger.

15. 7. In a labeling machine, the combination of a labeling compartment comprising side and rear walls, a plunger for directing articles through said compartment, a liner 25 yieldingly supported on one of said side walls, a front wall for said compartment, and adjustable means for maintaining said front wall in sliding engagement with said plunger.

20. 8. In a labeling machine, the combination of an open-front compartment, a plunger, means for yieldingly depressing said plunger to direct articles through said compartment, a front closure for said compartment, and means for maintaining said front closure in sliding engagement with said plunger.

25. 9. In a labeling machine, the combination of a labeling compartment comprising side and rear walls, a plunger for directing articles through said compartment, a front wall for said compartment extending upward 45 therefrom in sliding engagement with said plunger, and a resilient clip extending downward from said plunger to coöperate with said front wall to yieldingly support an article.

30. 10. In a labeling machine, the combination of a labeling compartment provided with walls, a plunger, means for depressing said plunger to direct articles through said compartment, and a resilient clip extending 55 downward from said plunger to coöperate with one of said walls for yieldingly supporting an article.

35. 11. In a labeling machine, the combination of a labeling compartment provided with walls, a plunger, means for depressing said plunger to direct articles through said compartment, a resilient clip carried by said plunger for coöoperating with one of said walls to yieldingly support an article, said clip being formed to engage an

other of said walls for releasing such supported article upon depression of said plunger.

40. 12. In a labeling machine, the combination of a labeling compartment provided with walls, a plunger, means for delivering articles alternately from opposite sides to said plunger, a resilient clip extending downward from said plunger to coöperate with one of said walls for yieldingly supporting such delivered articles, and means for depressing said plunger to direct such articles through said compartment.

45. 13. In a labeling machine, the combination of a labeling compartment comprising side and rear walls, a plunger, means for depressing said plunger to direct articles through said compartment, a front wall pivotally supported at the lower portion of said compartment, and adjustable means for maintaining said front wall in sliding engagement with said plunger.

50. 14. In a labeling machine, the combination of a paste platen, a traveling head, a label holder, means for firmly but removably latching said holder to said head, and means for reciprocating said head to successively feed a stock of labels to said platen.

55. 15. In a labeling machine, the combination of a labeling compartment, a series of chutes, a reciprocating feed device for delivering articles from said chutes to said compartment, and means for supplying labels alternately from opposite sides to said compartment.

60. 16. In a labeling machine, the combination of independent paste platens, means for feeding labels thereto, a common labeling compartment, a series of chutes, a reciprocating feed device for delivering articles from said chutes to said compartment, a gripper mechanism, and means for reciprocating said gripper mechanism for supplying labels alternately from said paste platens to said common compartment.

65. 17. In a labeling machine, the combination of a pair of paste platens, means for feeding labels thereto, a common labeling compartment, a series of chutes, a reciprocating feed device for delivering articles from said chutes to said compartment, a gripper plate, means for reciprocating said plate to supply labels alternately from said pair of platens to said common compartment, and stops in the path of said grips for controlling the gripping and releasing action of the latter.

70. 18. In a labeling machine, the combination of a paste platen, a label holder for containing a stock of labels, means for reciprocating said holder to successively feed such stock of labels to said platen, and a slidably-mounted stripper provided with a lip projecting over the top of such stock of

- labels for supporting said stripper by gravity.
19. In a labeling machine, the combination of a labeling compartment, means for feeding boxes and labels thereto, levers fulcrumed at opposite sides of said compartment, links pivoted to said levers, rollers carried at the free ends of said links, actuating means for shifting said levers from their normal retracted position, and a common means for maintaining said rollers in yielding engagement with the labels and boxes during such shifting of said levers and for returning the latter to their normal position.
20. In a labeling machine, the combination of supply chutes, a labeling compartment, a feed slide for feeding boxes from said chutes to said compartment, paste platens, holders for supplying labels to said platens, a gripper mechanism for conveying labels from said platens to said compartment, and a common, rigid, cam device for actuating said feed slide, paste platens, and gripper mechanism. 25

In testimony whereof I affix my signature in presence of two witnesses.

ROBERT E. FRIEDEIN.
